UNITED STATES PATENT OFFICE.

EDMUND C. MORGAN, OF CHICAGO, ILLINOIS.

AUTOMATIC COUNTERBALANCING SYSTEM FOR INCLINED RAILWAYS.

SPECIFICATION forming part of Letters Patent No. 772,733, dated October 18, 1904.

Application filed April 27, 1904. Serial No. 205,252. (No model.)

To all whom it may concern:

Be it known that I, EDMUND C. MORGAN, a citizen of the United States, residing at Chicago, in the county of Cook and State of Illinois, have invented a new and useful Automatic Counterbalancing System for Inclined Railways, of which the following is a specification.

This invention relates to automatic counter-balancing system for inclined railways.

The object of the invention is to provide a counterbalancing system for inclined railways which is simple and efficient.

A further object of the invention is to provide a counterbalancing system for inclined railways wherein the locomotive is required to perform as much work in descending the incline as in ascending the same.

A further object of the invention is to provide means whereby connection between the locomotive or train and the counterbalance is made and released automatically.

Other objects of the invention will appear more fully hereinafter.

The invention consists, substantially, in the construction, combination, location, and arrangement of parts, all as will be more fully hereinafter set forth, as shown in the accompanying drawings, and finally pointed out in the appended claims.

Referring to the accompanying drawings and to the various views and reference-signs appearing thereon, Figure 1 is a view in side elevation of a counterbalancing system for inclined railways embodying the principles of my invention. Fig. 2 is a top plan view of the same. Fig. 3 is a view in side elevation of a locomotive or car, showing a means whereby the counterweight is automatically connected and disconnected thereto. Fig. 4 is a top plan view of the construction shown in Fig. 3. Fig. 5 is a view in transverse section on the line 5 5, Fig. 3, looking in the direction of the arrows.

The same part is designated by the same reference-sign wherever it occurs throughout the several views.

In the operation of railroad systems, and particularly railroad systems employed in mine haulage, it is frequently necessary for

the locomotive and a train of cars drawn or propelled thereby to ascend and descend inclines or grades. In case the locomotive and the train hauled thereby is required to ascend a grade or an inclined portion of the road, especially where the cars of the train are loaded, the locomotive is required to develop an excessive amount of power in order to effect the ascent, and frequently the locomotive is taxed beyond its capacity when hauling heavy loads, thereby creating trouble and annoyance and resulting in a failure to effect the ascent. Similarly in descending the grade or incline with or without a load the locomotive is not called upon to perform any work and the brake appliances are frequently insufficient to check the rate of descent, thereby rendering the operation of the road dangerous.

In carrying out the principles of my invention I propose to employ means for counterweighting or counterbalancing the locomotive and train of cars hauled thereby when ascending and descending grades or inclines in the roadway in such manner that the motor or locomotive is required to develop practically as much power in descending as in ascending, thereby relieving the locomotive or motor of the excessive strains imposed thereon in hauling a loaded train up the grade and the danger of the locomotive or train running away when descending the grade or incline. In the accomplishment of this result I propose to employ a counterweight or counterbalance so relatively proportioned with reference to the weight of the locomotive, the cars of the train, and the load carried thereby as to equal the weight of the locomotive and cars and a portion of the load carried by the cars. For instance, suppose the weight of the locomotive is ten tons and of the train of cars hauled thereby when empty to be ten tons and the load on the cars to be, say, twenty tons. This will make the total weight being hauled up an inclined section or portion of the road equal to forty tons. I therefore propose to employ a counterweight of, say, thirty tons, thereby counterbalancing the weight of the locomotive and cars and half that of the load, and I arrange the counterbalance to be

raised while the locomotive and train descends the incline and the counterweight to be lowered when the locomotive and train ascends the incline. It is usual, especially in 5 the arrangement of railway systems in mines, to provide inclines or grades in the roadway connecting level portions of the track where the loaded cars are required to ascend the grade or incline and the empty cars to descend. Therefore it will be seen that in accordance with the principles of my invention in ascending the grade or incline the locomotive is called upon to develop only sufficient power to raise ten tons' weight of difference between the weight of the locomotive, cars, and load—say aggregating forty tons—and that of the counterweight—say thirty tons. It will also be seen that in descending the grade with a train of empty cars 15 20 25 30 35 40 45 50 55 60 65 70 75 80 85 90 95 100 105 110 115 120 125 130

the locomotive is called upon to develop practically the same amount of power—namely, that required to raise the counterweight, or ten tons—being the difference (in the instance given) between the weight of the counterweight (thirty tons) and of the combined weight of the locomotive and train of empty cars, (twenty tons.) Therefore the locomotive is called upon to develop substantially the same amount of power in descending as in ascending, being relieved of the necessity of developing excessive power in ascending and enabling the brake appliances to be more effective in preventing the locomotive and train of empty cars running away while descending. In the illustration given I have neglected the element of friction, which is a matter subject to adjustment according to various conditions of load.

Referring to the drawings, especially Figs. 1 and 2, wherein is illustrated a section of roadway, including a grade or inclined portion, and wherein is shown an application of a construction and arrangement embodying the principles of my invention, reference-sign A designates a level section of the track at one end of a grade or inclined section B, and C a level portion or section at the other end of the grade or incline, it being of course understood that the counterbalancing system embodying my invention is applied only at the grade. D designates the locomotive, and E cars of a train hauled thereby. F designates the counterweight, which may be of any suitable or convenient construction, the 55 special character of which is not of consequence, and G designates a cable or other connection arranged to be connected at one end to the locomotive or car and operating over suitable guide-sheaves H and connected 60 at its opposite end to the counterweight F. As merely illustrative of an operative embodiment of my invention, I employ as a counterweight a loaded car F, which affords a convenient construction and arrangement of counterweight, especially in the case of mine-haul-

age systems. It is obvious that the counterweight may be arranged to move in any desired manner. In the particular form shown, to which, however, my invention is not to be limited or restricted, I have shown the loaded car serving as a counterweight arranged to operate on an inclined track (indicated at J, Fig. 2) located adjacent to the main track or road-bed; but this, as above indicated, is merely an illustrative embodiment of the principles of my invention and to which I do not desire to be limited or restricted. 70 75 80 85 90 95 100 105 110 115 120 125 130

In the operation of a counterweighting or counterbalancing system such as above described it is desirable to provide means whereby the connection between the counterweight-cable and the locomotive, car, or train may be effected automatically and wherein disengagement between the counterweight-cable and the locomotive, car, or train may also be effected automatically. For instance, in case the locomotive or train descends the grade under the retarding influence of the counterweight imposed by the raising of the latter when the locomotive or train reaches the lower extremity of the grade or inclined section of the road and is ready to proceed along the adjacent level portion of the road-bed it is desirable to provide means whereby the cable which connects the counterweight to the locomotive or train may be automatically detached from the locomotive or train to permit the same to proceed on its journey, and at the same time it is desirable to provide means whereby the counterweight-cable is retained or held at such limit of its action, so as to prevent the counterweight from running wild to its lowermost position when released and so as to leave the cable connection in position at the lower limit of its action to be again picked up by the locomotive or train when it returns and is ready to ascend the grade or incline with its load. In Figs. 3, 4, and 5 I have shown as illustrative of an operative embodiment of means a construction whereby these desirable objects are accomplished and wherein the cable G is provided with a cross pin or bar K at the end thereof, the ends of which are arranged to be received transversely across the end of a block or lever L, suitably hinged or pivoted upon the car or locomotive D. The block or lever L is yieldingly maintained in elevated or raised position, as shown in Fig. 3, in any convenient manner—as, for instance, by means of a spring, (indicated in dotted lines at N.) When the cable is attached to the car or locomotive through the block or lever L—that is, when the ends of the cross-bar K of the cable bear against or are received in the seats formed to receive the same in the block or lever L—and the strain of the counterweight F is imposed upon the cable—as, for instance, when the locomotive is descending the grade or incline—the pull exerted upon the cable G, tending to hoist the coun-

terweight, is transmitted to the block or lever L in a line above the axis about which said block or lever is hinged or pivoted, thereby affording an additional locking means for 5 maintaining the block or lever L in elevated or raised position. The block or lever L is hinged or pivoted upon a shaft or rod P and concentric with such shaft or rod or in any other convenient or suitable manner with reference to such shaft or rod, whereby rotation imparted to such rod effects a rocking or swinging movement of the block or lever L. The shaft or rod P is provided at a convenient point—say, for instance, on the outer end 10 thereof—with a crank-arm O, said crank-arm having a lateral projection Q extending therefrom and arranged to be engaged by a coöperating lateral projection R, formed on the free end of a lever S, suitably hinged or pivoted upon a bracket or in any other convenient manner fixed adjacent to the road-bed upon which the truck, car, or locomotive operates. If desired, and preferably, the lever S is yieldingly maintained in raised position— 15 as, for instance, by means of the spring A'—and into position to engage over the projection Q of crank O as the car, truck, or locomotive descends the grade or incline, so as to rock or swing crank O downwardly upon its 20 axis to effect an automatic disengagement of the cable G from the car, truck, or locomotive. In practice the engaging lever S is preferably arranged at the foot of the grade or incline or at the beginning of the level portion 25 C of the system at the foot of such grade or incline. By yieldingly supporting the engaging lever S in raised position it will be readily seen that the locomotive may progress in a direction to proceed up the grade, riding 30 over lever S; but in descending the grade 35 or incline the truck, car, or locomotive to which the cable G is attached or connected reaches the upwardly-projecting lever S the lateral shoulder or projection R thereon will engage over the coöperating lateral projection Q of crank O, thereby rocking or swinging block or lever K downwardly against the action of its retractile N, and so as to carry the strain 40 or pull exerted by the cable G upon the block 45 or lever L below the pivotal axis of said block or lever L, and hence into position for the pull 50 exerted upon the cable to cause or effect a disengagement of the cable with the truck, car, or locomotive. As soon as this disengagement 55 occurs the projection R of lever S rides past the projection Q of block or lever L, thereby permitting said block or lever L to be returned to its raised position through the action of its retractile N. In this manner the 60 connection of cable G to the car, truck, or locomotive is automatically disengaged and at the point where such disengagement is desirable.

After the counterweight cable or connection 65 has been disconnected from the car it is desir-

able to provide means arranged to engage or to be engaged by the cable to hold the same whereby the elevated counterweight is prevented from running wild from the raised position occupied thereby at the time such disconnection of the cable from the car or locomotive is effected. To accomplish this result, I arrange at a convenient point in the road-bed or adjacent thereto a pivoted lever or block B', having a seat or seats (indicated at C', Fig. 70 75 3) to receive the cross-bar K of the counterweight-cable G and similar in this respect to the seats formed in the lever or block L, and I so relatively arrange the block or lever B' with reference to lever S and block or lever 80 L that when the car or locomotive arrives into position for the lever S to effect a downward rocking movement of block or lever L to disengage the cable from the car or locomotive the cable cross-bar K will be brought into position to slip from its seat in the lever or block L into the seat C' in lever or block B'. Preferably the lever or block B' is yieldingly held or maintained in lowered position—as, for instance, by means of a spring D' (see Fig. 3)— 85 90 and when the cable connection is transferred from the car or locomotive or from the block or lever L mounted thereon to the block or lever B' fixed in the road-bed the pull or strain exerted by the counterweight upon the cable 95 will be exerted upon lever or block B' in a line below the horizontal plane containing the axis about which the lever or block L rocks, thereby affording an efficient means for holding and anchoring the cable end. It will 100 be seen that when the block or lever L is sufficiently rocked, through the agency of lever S engaging crank-arm O sufficiently for the line of pull exerted by the cable to pass below the horizontal plane containing the axis about 105 which block or lever L rocks or swings the cross arm or bar K will snap off or out of engagement with the lever or block L, and hence the instant this occurs the lever or block B' should occupy such relative position with respect thereto as that the cross arm or bar K 110 will snap into engaging seat C' in said lever or block B'.
In accordance with the principles of my invention I propose to provide means whereby 115 after the cable G has been automatically disconnected from the car, truck, or locomotive after completing the descent of a grade or incline, as above explained, it proceeds along the level portion of the track (indicated at C, Fig. 1) to the desired point where the cars of the train receive their load—as, for instance, of coal—and returns to or approaches the grade or inclined section of the road. The locomotive, car, or truck automatically picks 120 up the cable end held or anchored, as above described, by the block or lever B' and replaces the same into engaging relation with respect to the block or lever L on the car, truck, or locomotive. In order to accomplish this 125 130

result, I provide the car, truck, or locomotive with a pivoted lever E' and having a lateral projection F' arranged to coöperate with a similar projection G', formed on or 5 projecting from block or lever B'. Preferably the lever E' is yieldingly pressed toward the limit of its downward movement. This may be accomplished in any convenient manner—as, for instance, by means of a spring 10 H' (see Fig. 3)—whereby the projection F' will ride idly over projection G' when the truck, car, or locomotive moves in one direction—say, for instance, down the incline or grade; but when the car, truck, or locomotive 15 travels in the opposite direction or approaches the incline or grade the projection F' on lever E' will engage underneath the projection G' on block or lever B', and thereby rock the latter about its hinged or pivotal 20 axis until eventually the line of pull exerted upon said block or lever B' by the counterweight acting through the cable is carried above the horizontal plane containing the axis of lever or block B', such rocking movement 25 of lever or block B' being against the action of spring D', and hence enabling the cross arm or bar K to snap out of the seat C' and to be disengaged therefrom. When this point is reached, the block or lever L is brought 30 into position to receive the cross arm or bar K of the cable, and hence the strain of the counterweight acting through the cable is transferred from the stationary anchoring device in the road-bed to the block or lever L 35 on the car, truck, or locomotive, thereby effecting automatically a picking up of the end of the counterweight-cable without arresting the locomotive or the train hauled thereby. It is obvious that any suitable arrangement 40 of limit-stops for the various levers and locking parts above described may be provided where necessary or desirable. For instance, the bracket or casting in which lever S is pivoted may be so formed as to constitute a 45 limit-stop to prevent said lever from being rocked too high, and similarly the bracket on which lever E' on the car or truck is pivoted may afford suitable means for limiting the extent of rocking or swinging movement of said 50 lever.

The car, truck, or locomotive may be of any suitable type or construction. Where an electric locomotive is employed, current may be supplied to the locomotive in any convenient 55 manner—as, for instance, through a trolley or other contact J' making contact with a suitably-arranged conductor K'.

From the foregoing description it will be seen that I provide an exceedingly simple arrangement of counterweighting or counterbalancing system and wherein the engagement 60 of the car, truck, or locomotive to be counterbalanced with the counterbalance-cable may be effected automatically and where- 65 in disengagement thereof may be effected au-

tomatically. When the car, train, or locomotive reaches the level section A of the track or roadway at the top of the incline or grade, the connection with the counterweight-cable may be disengaged and automatically in any 70 convenient manner, and similarly such cable may be automatically picked up as the locomotive, car, or train approaches the upper end of the incline preparatory to descending it in the same manner and by a similar arrangement to that above described with reference to the automatic disengagement and picking up of the cable at the bottom of the incline, or, if desired, the connection between the car, train, or locomotive and the cable 75 may be disconnected as the car, train, or locomotive reaches the top of the grade or incline in ascending by providing a suitable stop to arrest the counterweight at the lower limit of its movement, thereby rendering the cable 80 slack, and consequently enabling it to disengage itself. It will also be seen that I provide means for efficiently counterbalancing a locomotive and its train, whether loaded or unloaded, when ascending or descending grades 85 or inclines, automatically connecting and disconnecting the counterweighting or counterbalancing devices as the train proceeds along the road-bed, thereby boosting or assisting the locomotive to hoist its load up the grade 90 or incline and disconnecting the aiding or boosting means when the train reaches the level section of track along which it progresses.

It is obvious that many variations and 100 changes in the size, proportion, and relative arrangement of parts would readily suggest themselves to persons skilled in the art and still fall within the spirit and scope of my invention. I do not desire, therefore, to be limited 105 or restricted to the exact details of construction and arrangement shown in the drawings and set forth in the foregoing description; but,

Having now set forth the object and nature 110 of my invention and a construction embodying the principles thereof, what I claim as new and useful and of my own invention, and desire to secure by Letters Patent, is—

1. In a counterbalancing system for rail- 115 way-trains, the combination with a locomotive and its train of cars, of a counterweight, said counterweight proportioned to counterbalance the weight of the locomotive and cars and a portion of the load, and connections between the counterweight and the train, as and for the purpose set forth.

2. In a counterbalancing system for rail- 120 way-trains operating over roadways having grades or inclined portions, the combination with the train, of a counterweight arranged at the grade or incline in the roadway, said counterweight arranged to counterbalance the weight of the train and a portion of its load, and connections between the train and 125

counterweight whereby the locomotive of the train is required to perform the same amount of work in descending as in ascending the grade or inclined section of the road, as and for the purpose set forth.

3. The combination with a roadway having level sections and an intermediate inclined section, and a counterweight arranged at the inclined section, a cable connected at one end to said counterweight, guide-pulleys over which said cable operates, a locomotive, means for connecting the other end of said cable to said locomotive, and means for automatically disconnecting said connecting means, as and for the purpose set forth.

4. The combination with a roadway having level portions and an intermediate inclined portion, and a counterweight arranged at the inclined portion, a cable connected to said counterweight, a locomotive, guide-pulleys intermediate the locomotive and the counterweight over which said cable operates, and means for automatically connecting the opposite end of said cable to the locomotive, as and for the purpose set forth.

5. The combination with a roadway having level portions and an intermediate grade or inclined portion, of a car, train or locomotive, a counterweight therefor, a cable connecting the counterweight and the car, train or locomotive, an engaging connection for the cable carried by the car, train or locomotive, and an engaging connection for the cable fixed in the roadway, and means for automatically shifting the cable from one of said connections to the other, as and for the purpose set forth.

6. The combination with a roadway having an inclined section, a car, train or locomotive, a counterweight therefor, a cable extending from the counterweight to the car, train or locomotive, engaging connections pivotally mounted upon the car, train or locomotive, and in the roadway, respectively, and means for automatically rocking said connections to transfer the cable from one to the other, as and for the purpose set forth.

7. The combination with a roadway having an inclined section, a car, train or locomotive, a counterweight therefor, a cable extending from the counterweight to the car, train or locomotive, a cable connection carried by the car, train or locomotive, a cable connection mounted in the roadway, and means for transferring the cable from one of said connections to the other, as and for the purpose set forth.

8. The combination with a roadway having an inclined section, a car, train or locomotive, a counterweight therefor, a cable extending from the counterweight to the car, train or locomotive, a cable connection carried by the car, train or locomotive, a cable connection mounted in the roadway, and means for transferring the cable from one of said connections to the other without arresting the movement

of the car, train or locomotive along the roadway, as and for the purpose set forth.

9. The combination with a roadway having an inclined section, of a car, train or locomotive, a counterweight therefor, a cable extending from the counterweight to the car, train or locomotive, a cable connection carried by the car, train or locomotive, and comprising a pivoted block or lever, and a lever pivotally mounted in the roadway and operating to rock said block or lever on the car, train or locomotive to effect a disengagement of the cable therewith, as and for the purpose set forth.

10. The combination with a roadway having an inclined section, of a car, train or locomotive, a counterweight therefor, a cable connected to the counterweight, a connection movably mounted in the roadway with which the cable engages, and means carried by the car, train or locomotive, arranged to shift said movable connection to disengage the cable therefrom, as and for the purpose set forth.

11. A roadway having an inclined section, a car, train or locomotive, a counterweight therefor, a cable connected to the counterweight, a cable connection mounted in the roadway with which said cable engages, a cable connection carried by the car, train or locomotive, and means also carried by the car, train or locomotive for disengaging the cable from the roadway connection and transferring the same to the connection on the car, train or locomotive, as and for the purpose set forth.

12. A roadway having an inclined section, a car, train or locomotive, a counterweight therefor, a cable connected to the counterweight, a block or lever pivotally mounted upon the car, train or locomotive, a coöperating block or lever pivotally mounted in the roadway, said blocks or levers constituting engaging means for the cable, a lever carried by the car, train or locomotive and coöperating with the pivoted block or lever in the roadway, and a lever mounted in the roadway and coöperating with the pivoted block or lever on the car, train or locomotive, whereby the cable connection may be transferred automatically from one of said blocks or levers to the other, as and for the purpose set forth.

13. A roadway having an inclined section, a car, train or locomotive, a counterweight therefor, a cable connected to said counterweight, guide-pulleys for said cable, a pivotally-mounted block or lever mounted upon the car, train or locomotive, arranged to form an engaging connection for said cable, a block or lever pivotally mounted in the roadway, also arranged to form a connection for said cable, operating-levers pivotally mounted, respectively, upon the car, train or locomotive, and in the roadway, and extending in opposite directions, and coöperating, respectively, with said cable connections, whereby the cable is transferred automatically from

one of said blocks or levers to the other according to the direction of travel of the car, train or locomotive, as and for the purpose set forth.

- 5 14. A roadway having an inclined section, a car, train or locomotive operating thereover, a counterweight therefor, a cable connected to said counterweight, a movable part mounted upon the car, train or locomotive, to afford 10 means for connecting the cable thereto, a co-operating movable part mounted in the roadway and arranged to form a connection for the cable, said movable parts each provided with a lateral projection, levers pivotally 15 mounted upon the car, train or locomotive,

and in the roadway, respectively, and provided with co-operating lateral projections co-operating with the lateral projections upon said movable members to rock the latter to transfer the cable from one to the other of 20 said movable members, according to the direction of progress of the car, train or locomotive, as and for the purpose set forth.

In witness whereof I have hereunto set my hand, this 11th day of April, 1904, in the presence of the subscribing witnesses.

EDMUND C. MORGAN.
